COMPOUND OF THE ABIETENE FAMILY

Clyde O. Henke, South Milwaukee, and Malcolm Charlton, Milwaukee, Wis., assignors, by
mesne assignments, to E. I. du Pont de Nemours & Company, a corporation of Delaware

No Drawing. Application May 25, 1931
Serial No. 540,010

11 Claims. (Cl. 260—64)

This invention relates to novel compounds of the abietene family.

More particularly this invention relates to novel condensation products obtainable by reacting sulfonic acids of the abietene family with aldehydes.

10 By the term "sulfonic acids of hydrocarbons of the group consisting of abietene, abietine and abietane" we mean the products obtained by sul-
15 fonating a compound containing the abietene nucleus, such as abietene, abietine, or abietane. The first two, abietene and abietine, are derivable by pyrogenic decomposition of rosin, abietic acid, or abietyl chloride. Abietane is obtainable by hydrogenating abietene. Methods of preparing
20 these compounds as well as their sulfonation products, are described in the copending application of Gubelmann and Henke Serial No. 431,626, filed Feb. 26, 1930, and in U. S. Patents Nos. 1,853,348, 1,853,352, and 1,853,353. However,
25 our invention is not limited to the particular derivatives obtainable by the particular methods disclosed in said copending applications. Many varieties of abietene or abietine are known in the art, (see for instance, Ruzicka, *Helv. Chim. Acta*, vol. 6, pages 638-640). The sulfonation products of any of these derivatives, obtainable according to the above mentioned copending applications or according to any well known method, are suitable for our invention.

30 We have now found that the above defined
sulfonic acid compounds of the abietene, abietane
and abietine hydrocarbons combine readily with
aldehydes to give novel and useful, water-soluble
compounds. The chemical nature of these com-
35 pounds is not quite understood, but it is probable
that they belong to the family of polyarylmethanes, and are formed, for example, according
to the following equations:

In Equation 2 "R" stands for a hydrogen atom or an alkyl or aryl group.

Our novel condensation products are, in the
50 form of their free acids, soluble in water and in

benzene, but insoluble in 50% sulfuric acid. Upon evaporation from a benzene solution they form a black pasty material. Their sodium salts are quite stable and may be stored indefinitely without decomposition.

The aldehyde condensation products, like the uncondensed sulfonic acid derivatives of the abietene, abietine and abietane hydrocarbons, form excellent wetting, dispersing and tanning agents both in the form of the free acids, or in the form of their alkali metal salts. They are therefore very useful commercially both in the textile and leather industries. Thus the addition of our novel compounds to any aqueous treatment bath for textile fibers, for instance in dyeing, bleaching, scouring and cleansing fiber, yarn or cloth, facilitates the penetration of the fiber by the liquid, improves the uniformity of the treatment, shortens the time of the treatment, and in general increases the efficiency of the entire operation. Addition of these compounds to tanning baths reduces the amount of natural tanning agent required, accelerates the time of tanning, and improves the color and texture of the leather.

The preparation of our novel products may be effected by dissolving the particular abietene, abietine or abietane sulfonic acid body in concentrated sulfuric acid and adding the particular aldehyde chosen. It is more advantageous, however, to add the aldehyde directly into the sulfonation mass in which the sulfonic acid body is formed, thereby saving the step of isolating the intermediate sulfonic acid body. Upon the addition of the aldehyde a vigorous reaction takes place with liberation of heat. After a few hours the entire mass becomes so viscous that it is difficult to stir. Dilution of the entire mass with water at this point, causes a separation of the mass into layers, the upper layer containing the condensed sulfonic acid body, while the lower layer contains the aqueous sulfuric acid. 90

The following examples will serve further to illustrate our invention, without however, limiting the same. Parts given are parts by weight.

Example 1

1000 parts of sulfuric acid monohydrate are placed in a sulfonation vessel fitted with an agitator, and cooled to about 10° C. 500 parts of abietene, such as for example, the product ob- 100

tained from grade B or grade FF wood rosin, by heating the same at reflux temperatures until its acidity substantially disappears as is more fully described and claimed in the copending application of Henke, Serial No. 540,007, filed of even date herewith and in U. S. Patent 1,853,353, are then dropped in slowly over a period of 4 hours, and the agitation continued for about 20 hours more. The entire mass is maintained at a 10 temperature of 5 to 10° C. by means of external cooling during this treatment. 100 parts of a 40% aqueous solution of formaldehyde are next added, and the stirring is continued for about 2 hours. The reaction mass is now poured into 1000 parts 15 of water, stirred thoroughly, and allowed to settle. The lower, aqueous, acid layer is discarded. The upper layer, which contains the formaldehyde-abietene-sulfonic-acid condensation product is dissolved in water, neutralized with caustic 20 soda, filtered, and evaporated to dryness. The yield of the condensation mass is about 700 parts.

If desired, instead of evaporating the neutralized filtration mass the latter may be extracted with benzene, and the extracted aqueous mass 25 evaporated to dryness. The product thus obtained is considerably purer and better in its practical qualities than the product obtained without benzene extraction. The latter step apparently removes any residual unsulfonated oil. 30 Instead of the 100 parts of a 40% formaldehyde solution above specified, 30 parts of paraformaldehyde may be used, all other conditions remaining the same. The product is similar in properties to the product above described.

35 Example 2

The procedure is the same as in Example 1, except that instead of 500 parts of abietene therein mentioned, 500 parts of abietane are used. The latter may be obtained by the hydrogenation of 40 abietene in the presence of a catalyst as is more fully described and claimed in the copending application of Gubelmann and Henke, Serial No. 431,626, filed Feb. 26, 1930. The final product has substantially the same properties as the 45 product of Example 1, and like the product of Example 1 may be further improved by extracting its aqueous sodium salt solution with benzene.

Example 3

50 110 parts of benzaldehyde are used instead of 100 parts of 40% formaldehyde as described in Example 1 and all the other details of Example 1 are maintained. The product is similar to that obtained in Example 1. It is evidently a condensation product of 2 mols of abietene and 1 mol of benzaldehyde.

Instead of using 110 parts benzaldehyde, 155 parts of benzal-chloride may be used. In this case hydrochloric acid is liberated during the reaction, which either escapes as a gas or finds its way into the aqueous layer in the dilution step.

The products obtained in Examples 1, 2, and 3, especially after extraction with benzene, are 65 excellent "Syntans", that is synthetic tanning agents, and are very useful as assistants to the natural tanning agents used in the ordinary processes of tanning hide. The tanning process when mixtures of our novel condensation products and natural tanning agents are used, is considerably simplified and accelerated. Moreover, the resultant leather excels in color and texture.

Example 4

75 28 parts of the benzene-extracted product ob-

tained in Example 1 are dissolved in 84 parts of water. 448 parts of sumac extract are added, and the mixture is diluted with 1500 parts of water. 1000 parts of pickled sheepskin are now introduced, and the entire mass is agitated in a 80 drum for about 3 to 4 hours. At the end of this period the sheepskin has become converted into leather of lighter color and better texture than leather obtainable by the use of sumac extract alone. It will also be noted that the time required for tanning has been reduced to about $\frac{1}{3}$ of that normally required when using sumac extract alone, and that the quantity of the sumac extract necessary has been reduced by about 20% compared to what would be required to produce 90 the same tanning effect, if it were used alone.

The process of using our novel compounds in tanning is claimed in the copending application of Henke and Orthmann, Serial No. 540,009, filed 95 of even date herewith.

The tannin equivalent of our novel condensation products, when determined by the American Leather Chemists Association method, runs about 40 to 50% of the weight of the product.

Other and further modifications may be introduced in our invention without departing from the spirit of the same.

Besides aldehydes in general, compounds which react like aldehydes in condensation reactions may be used in our process such as, for example, 105 paraformaldehyde and benzal-chloride.

We claim:

1. The process of producing water soluble compounds which comprises condensing a sulfonic acid body of hydrocarbons of the group consisting of abietene, abietine and abietane with a member of the group consisting of aldehydes and compounds which react like aldehydes.

2. The process of producing water soluble compounds which comprises reacting a sulfonic acid 115 body of a hydrocarbon selected from the group consisting of abietene, abietine and abietane in concentrated sulfuric acid with a member of the group consisting of aldehydes and compounds which react like aldehydes.

3. The process of producing water soluble compounds which comprises condensing sulfonic acids of hydrocarbons of the group consisting of abietene, abietine and abietane with formaldehyde.

4. The process of producing water soluble compounds which comprises condensing sulfonic acids of hydrocarbons of the group consisting of abietene, abietine and abietane with benzaldehyde.

5. The process of producing water soluble compounds which comprises reacting upon a hydrocarbon of the group consisting of abietene, abietine and abietane with sulfuric acid, adding a member of the group consisting of aldehydes and 135 compounds which react like aldehydes to the sulfonation mass and recovering the reaction product.

6. A water soluble condensation product of a sulfonic acid body of hydrocarbons selected from 140 the group consisting of abietene, abietine and abietane with a member of the group consisting of aldehydes and compounds which react like aldehydes.

7. A water soluble condensation product of sulfonic acids of hydrocarbons of the group consisting of abietene, abietine and abietane with formaldehyde.

8. A water soluble condensation product of a sulfonic acid body of hydrocarbons selected from 150

the group consisting of abietene, abietine and abietane with benzaldehyde.

9. A water soluble compound having most probably the following formula:

in which R stands for a hydrogen atom or an alkyl 10 or aryl group.

10. The process of producing water soluble

compounds which comprises condensing a sulfonic acid body of hydrocarbons selected from the group consisting of abietene, abietine and abietane with benzal-chloride.

11. A water soluble condensation product of a sulfonic acid body of hydrocarbons selected from the group consisting of abietene, abietine and abietane with benzal-chloride.
